G. H. CURTISS.
AEROPLANE CONSTRUCTION.
APPLICATION FILED JAN. 29, 1917.

1,295,084.

Patented Feb. 18, 1919.

FIG. 1.

By

UNITED STATES PATENT OFFICE.

GLENN H. CURTISS, OF BUFFALO, NEW YORK, ASSIGNOR TO CURTISS AEROPLANE AND MOTOR CORPORATION, A CORPORATION OF NEW YORK.

AEROPLANE CONSTRUCTION.

1,295,084.

Specification of Letters Patent. Patented Feb. 18, 1919.

Original application filed September 6, 1912, Serial No. 718,840. Divided and application filed June 4, 1913, Serial No. 771,646. Divided and application filed June 7, 1915, Serial No. 32,654. Divided and this application filed January 29, 1917. Serial No. 145,138.

To all whom it may concern:

Be it known that I, GLENN H. CURTISS, a citizen of the United States, residing at Buffalo, in the county of Erie and State of New York, have invented certain new and useful Improvements in Aeroplane Construction, of which the following is a specification.

This invention relates to aircraft and has reference more particularly to the various aeroplane features of an hydro-aero machine, or more properly a flying boat, disclosed in a parent application, S. N. 718,840, filed Sept. 6th, 1912, and subsequently patented as Patent #1,085,575, granted Jan. 27, 1914. Since the filing of said parent application, divisional applications have been filed. Application S. N. 771,646, filed June 4, 1913, is a division of said parent case, application S. N. 32,654, filed June 7, 1915, a division of said divisional case, and the present application, a division of application S. N. 32,654.

The characteristic features of the basic hydroaero-machine intended to be covered by the present application are both constructional and ornamental in their nature. The structural features may be generally described as comprising an improved supporting surface arrangement, an improved empennage arrangement, and an improved arrangement of the power plant and its bracing and supporting means. The ornamental features are apparent upon reference to the drawings, particularly Figure 1, wherein the ornamental lines of the hull are clearly portrayed. Other features such as the arrangement of the supporting surface braces and the variation in the span of the respective supporting surfaces are also intended to be covered herein.

Of the drawings:

Fig. 1 is a side elevation of the entire machine (partly broken away), and

Fig. 2 is a front elevation of the same.

The hull of the body of the craft, designated in its entirety by the numeral 10, is essentially pleasing to the eye and from a mechanical point of view is intermediately equipped with supporting surfaces 11 and 12 which extend transversely across said body in lifting relation thereto. The upper supporting surface 11 from tip to tip is of

greater length or span than the lower supporting surface 12. The planes or wings 55 constituting said upper surface are arranged in substantially the same horizontal plane. The wings constituting the lower surface however, are arranged in intersecting planes or at a dihedral angle. This variation in the 60 arrangement of the several planes makes for greater stability incident to flight. The terminals of the upper supporting surface 11, by reason of its greater length or span, overhang the terminals of the lower supporting 65 surface 12 as indicated at 13. Thus the lifting efficiency of the upper surface is greater than that of the lower surface, and lateral stability, by reason of the overhung portions 13, further increased.

Moreover, the effective area of the upper surface 11, is increased by extending said surface rearwardly, as indicated at 13', in the vicinity of the respective surface terminals. These rearwardly extending portions 75 are acted on primarily by the laterally and rearwardly slipping air, escaping from beneath the surface 11 during flight.

Wing posts 14 interconnect the surfaces 11 and 12, the wing posts designated 14' defining the engine section of the craft. Said engine section is characterized by the support of the power plant, designated in its entirety by the numeral 15, intermediate the supporting surfaces with its center of mass 85 in the approximate vertical plane of the fore and aft axis of the craft.

Engine bed beams 16 support the power plant above the hull. These beams 16 are in turn supported by braces or supports 17 90 erected on the lower supporting surface 12 to converge upwardly for termination at the engine bed. Braces 18 continue the supports 17 at an angle to the upper supporting surface 11. These braces 18, converge downwardly to vertically brace the engine bed. Lateral strains are transmitted from the power plant to the wing posts 14' which define the engine section by braces 19 disposed horizontally and in the plane of the engine bed.

The wing structure, in its entirety, and the power plant, are braced laterally inwardly from a point at the foot of the wing posts 14' and braces 17 to the sides of the 105 hull or body 10 by diagonally extending

braces 20 disposed at opposite sides of the hull. These braces (see Fig. 2) effectually transmit landing inertia strains, via the lower supporting surface 12, to the hull.

5 Said lower supporting surface, or rather the wings constituting said surface, it will be noted, are founded upon the hull to extend laterally considerably therebeyond. Said wings may be described as anchored to and 10 upon the top surface of the hull, although it is sufficient that they be attached directly to the hull at a safe operating distance above the water.

The empennage of the craft comprises the 15 usual vertical stabilizer 21, horizontal stabilizer 22, rudder 23 and elevator flaps 24; the two stabilizers, and the rudder and the elevator flaps intersecting. The vertical stabilizer 21 is erected upon the hull 10 and the 20 horizontal stabilizer arranged considerably above the hull to intersect said vertical stabilizer in the plane of the elevator flaps 24. This arrangement of the horizontal stabilizer above the hull is conducive to increased effective stabilizing surface. Moreover, the 25 horizontal stabilizer is thus sufficiently vertically removed from the surface of the water to prevent it from coming in contact with the water or with flying spray under all 30 operating conditions.

Forwardly of the supporting surfaces 11 and 12, the hull is equipped with a cockpit 25 within which the aviator's or pilot's seat 26 is disposed. For convenience in operation 35 a cranking device 27 is located in such proximity to the seat 26 as to permit operation of said cranking device conveniently from the cockpit 25.

Such parts of the craft as the propeller 40 28, control mechanism 29, wing pontoons 30 and ailerons 31 are detailed and claimed in said pending applications.

While I have described my invention in detail in its present preferred embodiment, 45 it will be obvious to those skilled in the art after understanding my invention, that various changes and modifications may be made therein without departing from the spirit or scope thereof. I aim in the appended claims 50 to cover all such modifications and changes.

What is claimed is:

1. In a flying boat, the combination of a hull adapted to support the structure by dis-

placement when at rest upon the water, supporting surfaces extending out laterally from the hull nearer the forward end than the rear end thereof, the inner ends of the wings constituting said surfaces being secured directly to the hull structure, said hull at the point of attachment of the wings thereto extending a sufficient height above the water to support the inner ends of the wings at a safe operating distance from the water at all stages of operation of the boat, a propelling power plant mounted above the hull likewise nearer its forward end than its rear end, and a horizontal stabilizer vertically spaced above the tail end of the hull, a safe operating distance from the water.

2. In a flying boat, the combination of a hull adapted to support the structure by displacement when at rest upon the water, supporting surfaces extending out laterally from the hull, the inner ends of said wings being secured directly to the hull structure, said hull at the point of attachment of the wings thereto extending a sufficient height above the water to support the inner ends of said wings at a safe operating distance above the water, a power unit mounted above the hull structure, supports extending angularly upwardly from the lower supporting surface to support the power unit in its elevated position, and braces extending from the lower supporting surface at opposite sides of the hull inwardly thereto for attachment to the sides of the hull, the braces at their upper ends engaging beneath the points of attachment of the angular supports with the lower supporting surface.

3. In a flying boat, the combination of a hull adapted to support the structure by displacement when at rest upon the water, supporting surfaces extending out laterally from the hull, a vertical stabilizing surface attached directly to the tail end of the hull, and a horizontal stabilizing surface mounted to intersect the plane of the vertical stabilizing surface above the tail end of the hull and sufficiently removed from it to space the horizontal stabilizer a safe operating distance above the water line when the boat is at rest upon the water.

In testimony whereof I affix my signature.

GLENN H. CURTISS.
